TOY

David Kirkwood Holliday, Mount Pleasant, Ohio

Application June 2, 1945, Serial No. 597,237

9 Claims. (Cl. 46—118)

1

This invention relates to a toy, and more particularly to a toy of the animated type.

A primary object of this invention is the provision of an improved toy, adapted for the edification and amusement of children or the like including a plurality of movable figures in simulation of a hunter and a hunted bird or animal.

An additional object of this invention is the provision of such a device wherein both the hunter and the game are movable, and wherein means are provided to simulate the sound of the shot.

An additional object of the invention is the provision of means in association with the device, whereupon with the aforementioned simulated shot the game is caused to fall in such manner as to indicate that same has been shot by the hunter.

An additional object of this invention is the provision of such a device characterized by simplicity and durability in construction, reliability and efficiency in operation, and simplicity and economy in manufacture and assembly.

Other objects will in part be obvious and in part be pointed out as the description of the invention proceeds and shown in the accompanying drawings wherein there is shown a preferred embodiment of this inventive concept.

In the drawings:

Figure 1 is a side elevational view of one form of device embodying this inventive concept, certain concealed portions thereof being indicated in dotted lines.

Figure 2 is a top plan view of the structure shown in Figure 1.

Figure 3 is a bottom plan view of the device.

Figure 4 is a sectional view taken substantially along the line 4—4 of Figure 2, as viewed in the direction of the arrows.

Figure 5 is an end elevational view of the device, certain parts thereof being removed.

Figure 6 is a top plan view of a constructional detail.

Figure 7 is a top plan view of an additional constructional detail, and

Figure 8 is a sectional view taken substantially along the line 8—8 of Figure 7, as viewed in the direction indicated by the arrows.

Similar reference characters refer to similar parts throughout the several views of the drawings.

The device of the instant invention is comprised of a base generally indicated at 10, in the form of an elongated block of any desired suitable length to which are secured a plurality of legs 11, as by screws 12, supporting the same a slight

2

distance above the floor, or table, or other supporting surface therefor. As best shown in Figure 5, the block 10 is provided with a longitudinally extending channel 13, having grooves 14 at the base thereof. Positioned for sliding movement within the channel 13 are two block members 15 and 16, each provided adjacent its base with longitudinally extending flanges 17 and 18, respectively, adapted to engage and slide in the grooves 14.

The block 15 is provided with a figure 19 in simulation of a hunter and provided with a rifle 20, while the block 16 has pivotally mounted thereon, as on a hinge member comprised of two sections 21 and 22 pivotally secured together as by means of the pivot pin 23 (see Figure 8), a figure 24, in simulation of game to be shot by the hunter. In the illustrative embodiment this figure takes the form of a duck but obviously any representation of an animal or other game may be substituted therefor. The blocks 15 and 16 are secured together, as by means of the cord 25 secured to eyes 26 and 27 in the front and rear portions of blocks 15 and 16 respectively, while secured to an eye 28 in the rear of block 15 is a cord 29, which extends to and is wound about an axle 30, provided with a handle 31 for rotating the same, and positioned between the rear pair of supporting members 11 being journaled for rotation in suitable apertures in the supporting members. From an eye 32 in the front of block 16 a cord 33 extends to an axle 34 journaled between the other pair of supports 11, and correspondingly provided with a handle or crank member 35 for rotating the same. As best shown in Figures 1 and 3 the cords 29 and 33 pass respectively over transversely positioned guide bars 36 and 37 positioned across the ends of the channel 13, and of cylindrical cross section, which serves as bearings for the respective cords.

From the foregoing it will now be seen that rotation of the crank or handle 35, occasions the forward movement of both blocks 16 and 15, through the connections above described, forwardly in the channel 13, in such manner as to indicate that the bird 24 is attempting to escape from the hunter 19, and the hunter is following the bird. Obviously, rotation of the handle 31 serves to draw the assemblage in the opposite direction.

Means are provided for simulating the sound of the shot from the hunter, and such means take the form of a clapper or hammer arm 40 pivotally connected as on a pivot 41, to the side of the block 10, and adapted when struck by an extend-

ing trip 42 mounted on the block 15, to fall by gravity and strike against a metallic clap plate or anvil 43 secured to the base of the block in any desired manner. The parts are so arranged that simultaneously with the falling of the member 40 the bird 24 is adapted to fall on its side, such movement being permitted by the pivot 23. Such means take the form of a trip 45 pivotally secured as on a pivot 46 to the block 10 and adapted to extend forwardly into the path of movement of the duck, a tapered extremity 47 being provided for abutment with the duck, to cause the same to tilt about the hinge and fall to its side. A stop pin 48 is provided, which holds the device at right angles to serve as a trip, when the assemblage including the duck 24 is moved forwardly, but when the direction of the movement of the assemblage is reversed as by rotation of the crank 31, the member 45 may pivot to permit passage of the duck 24 therewith.

Correspondingly, the member 40 is provided with a right angled arm 49, which extends upwardly into the path of the nail or trip finger 42, after the member has been tripped, and when the assemblage is moved rearwardly impact of said nail 42 against the extending arm 49 causes the member 40 to be reset in the position shown in Figure 1.

From the foregoing it will be seen that there is herein provided a toy of the animated figure type, which provides a relatively high entertainment value, which simulates a hunter in pursuit of game, and likewise the shooting of the game by the hunter, and the fall of the game as a result of the shot which accomplishes all the objects of this invention, and others including many advantages of great practical utility and commercial importance.

As many embodiments may be made of this inventive concept, and as many modifications may be made in the embodiment hereinbefore shown and described, it is to be understood that all matter herein is to be interpreted as merely illustrative and not in a limiting sense.

I claim:

1. In a device of the character described, a base, a longitudinal channel therein, spaced blocks movable in said channel, figures in simulation of hunter and game carried by said blocks, means for moving said blocks, said means including cords secured to the opposite ends of said blocks, axles mounted at opposite ends of said base, about each of which one of said cords is wound, means for rotating said axles, means for simulating the sound of a shot by said hunter, said last-mentioned means including a trip member pivoted on a side of said base, an anvil adapted to be struck by said trip member, an extending member carried by one of said blocks to operate said trip member, said figure in simulation of game being pivotally mounted on its associated block, and means to tilt said last-mentioned figure simultaneously with said simulated shot.

2. In a device of the character described, a base, a longitudinal channel therein, spaced blocks movable in said channel, figures in simulation of hunter and game carried by said blocks, means for moving said blocks, said means including cords secured to the opposite ends of said blocks, axles mounted at opposite ends of said base, about each of which one of said cords is wound, means for rotating said axles, means for simulating the sound of a shot by said hunter, said last-mentioned means including a trip member pivoted on a side of said base, an anvil adapted to be struck

by said trip member, an extending member carried by one of said blocks to operate said trip member, said figure in simulation of game being pivotally mounted on its associated block, and means to tilt said last-mentioned figure simultaneously with said simulated shot, said last-mentioned means including a second trip member in the path of movement of said last-mentioned figure, and spaced from said first trip member a distance equal to the spacing of said blocks.

3. A toy including a base, a plurality of legs supporting said base, a longitudinally extending channel in said base, a block slideable in said channel surmounted by a figured simulation of a hunter, a windlass mounted below each end of said base and supported between oppositely disposed legs, means secured to each windlass and to opposite ends of said block, means for simulating the sound of a gun shot, said means including an anvil and a striker secured to the side of said base, said striker comprising an arm pivoted at its lower end to said base above said anvil, and an operating means extending laterally of said block for engaging said striker arm, and a target, said target being hinged for movement in a vertical plane transverse to said base, and means for tripping said target about its hinge, said last named means being synchronized for simultaneous actuation with said striker.

4. A toy including a base, a plurality of legs supporting said base, a longitudinally extending channel in said base, a block slideable in said channel surmounted by a figured simulation of a hunter, a windlass mounted below each end of said base and supported between oppositely disposed legs, means secured to each windlass and to opposite ends of said block, means for simulating the sound of a gun shot, said means including an anvil and a striker secured to the side of said base, said striker comprising an arm pivoted at its lower end to said base above said anvil, and an operating means extending laterally of said block for engaging said striker arm, and a target, said target being hinged for movement in a vertical plane transverse to said base, and means for tripping said target about its hinge, said last named means being synchronized for simultaneous actuation with said striker, said target being carried by a second block slideable on said channel.

5. A toy including a base, a plurality of legs supporting said base, a longitudinally extending channel in said base, a block slideable in said channel surmounted by a figured simulation of a hunter, a windlass mounted below each end of said base and supported between oppositely disposed legs, means secured to each windlass and to opposite ends of said block, means for simulating the sound of a gun shot, said means including an anvil and a striker secured to the side of said base, said striker comprising an arm pivoted at its lower end to said base above said anvil, and an operating means extending laterally of said block for engaging said striker arm, and a target, said target being hinged for movement in a vertical plane transverse to said base and means for tripping said target about its hinge, said last named means being synchronized for simultaneous actuation with said striker, said target being carried by a second block slideable on said channel, said second block being secured in fixed position to said first block.

6. A toy including a base, a plurality of legs supporting said base, a longitudinally extending

channel in said base, a block slideable in said channel surmounted by a figured simulation of a hunter, a windlass mounted below each end of said base and supported between oppositely disposed legs, means secured to each windlass and to opposite ends of said block, means for simulating the sound of a gun shot, said means including an anvil and a striker secured to the side of said base, said striker comprising an arm pivoted at its lower end to said base above said anvil, and an operating means extending laterally of said block for engaging said striker arm, and a target, said target being hinged for movement in a vertical plane transverse to said base and means for tripping said target about its hinge, said last named means being synchronized for simultaneous actuation with said striker, said target being carried by a second block slideable on said channel, said second block being spaced from said first block and interposed between said first block and one of such windlass secured means.

7. A toy including a base, a plurality of legs supporting said base, a longitudinally extending channel in said base, a block slideable in said channel surmounted by a figured simulation of a hunter, a windlass mounted below each end of said base and supported between oppositely disposed legs, means secured to each windlass and to opposite ends of said block, means for simulating the sound of a gun shot, said means including an anvil and a striker secured to the side of said base, said striker comprising an arm pivoted at its lower end to said base above said anvil, and an operating means extending laterally of said block for engaging said striker arm, and a target, said target being hinged for movement in a vertical plane transverse to said base and means for tripping said target about its hinge, said last named means being synchronized for simultaneous actuation with said striker, said target being carried by a second block slideable on said channel, said last mentioned means including a member carried by said base and extending into the path of travel of said target for tilting the latter.

8. A toy including a base, a plurality of legs supporting said base, a longitudinally extending channel in said base, a block slideable in said channel surmounted by a figured simulation of a hunter, a windlass mounted below each end of said base and supported between oppositely disposed legs, means secured to each windlass and to opposite ends of said block, means for simulating the sound of a gun shot, said means including an anvil and a striker secured to the sides of said base, said striker comprising an arm pivoted at its lower end to said base above said

anvil, said operating means extending laterally of said block for engaging said striker arm, and a target, said target being hinged for movement in a vertical plane transverse to said base and means for tripping said target about its hinge, said last named means being synchronized for simultaneous actuation with said striker, said target being carried by a second block slideable on said channel, said last mentioned means including a member carried by said base and extending into the path of travel of said target for tilting the latter, said member having a longitudinally inclined transversely extending edge for engaging said target.

15 9. A toy including a base, a plurality of legs supporting said base, a longitudinally extending channel in said base, a block slideable in said channel surmounted by a figured simulation of a hunter, a windlass mounted below each end of said base and supported between oppositely disposed legs, means secured to each windlass and to opposite ends of said block, means for simulating the sound of a gun shot, said last means including an anvil and a striker secured to the side of said base, said striker comprising an arm pivoted at its lower end to said base above said anvil, and an operating means extending laterally of said block for engaging said striker arm, and a target, said target being hinged for movement in a vertical plane transverse to said base and means for tripping said target about its hinge, said last named means being synchronized for simultaneous actuation with said striker, said target being carried by a second block slideable on said channel, said last mentioned means including a member carried by said base and extending into the path of travel of said target for tilting the latter, said member being pivoted to said base.
